UNITED STATES PATENT OFFICE

121,703

DESIGN FOR A WALL SWITCH PLATE

Emory A. Seward, Chicago, Ill.

Application October 9, 1939, Serial No. 87,596

Term of patent 3½ years

To all whom it may concern:

Be it known that I, Emory A. Seward, a citizen of the United States, residing at Chicago, in the county of Cook and State of Illinois, have invented a new, original, and ornamental Design for a Wall Switch Plate, of which the following is a specification, reference being had to the accompanying drawing, forming part thereof.

Figure 1 is a plan view of the wall switch plate showing my new design.

Figure 2 is a side elevation thereof.

The design resides in the wall switch plate including in its upper part the flat cut-out figure shown.

I claim:

The ornamental design for a wall switch plate, as shown and described.

EMORY A. SEWARD.
